CLAIM

The ornamental design for a bead with square hole, as shown and described.

DESCRIPTION

FIG. 1 is a perspective view of a bead with square hole showing my new design;

FIG. 2 is a front view thereof;

FIG. 3 is a first side view thereof;

FIG. 4 is a top view thereof; and,

FIG. 5 is a bottom view thereof.

The broken lines in the drawings form no part of the claimed design.
